(57) **CLAIM**

The ornamental design for a lighted support base for containers, as shown and described.

DESCRIPTION

FIG. 1 is a front perspective view of the lighted support base for containers of the instant invention;

FIG. 2 is a front plan view thereof;

FIG. 3 is a rear plan view thereof;

FIG. 4 is a left plan view thereof, the right plan view being a mirror image thereof;

FIG. 5 is a top plan view thereof;

FIG. 6 is a bottom plan view thereof; and,

FIG. 7 is a front perspective view illustrating the instant invention supporting a container.

The broken line showing of the container is included for the purpose of illustrating the container and forms no part of the claimed design.
